CARPET.

No. 15,484.

Patented Oct. 28, 1884.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 15,484, dated October 28, 1884.

Application filed August 6, 1884. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The face of the design is closely filled in with interblent flower and leaf figures, without conspicuous grouping or regular arrangement. A Greek-letter ornament appears in the inter-

stices of the design between the overlying flower and leaf figures. 20

The design is clearly shown in the accompanying photograph, to which design as there shown, or one substantially the same, my claims are limited.

I claim—

1. The design for a carpet, consisting of the interblent flower and leaf figures, substantially as shown and described. 25

2. The design for a carpet, consisting of the interblent flower and leaf figures and the underlying Greek-letter ground, substantially as shown and described. 30
